(57) **CLAIM**

The ornamental design for a tablet computer stand, as shown and described.

DESCRIPTION

FIG. 1 is a front perspective view of a tablet computer stand showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is a rear perspective view thereof.

FIGS. 1-8 include surface shadings. The different surface shadings (line shading and stippled shading) in FIGS. 1-8 are used to indicate contrasting materials.

1 Claim, 6 Drawing Sheets
